REFRIGERATING APPARATUS FOR THE STORAGE AND PRESERVATION OF FOOD, DELICACIES, AND THE LIKE

Johan Frederik Ingvar Ingvardsen and Erik Anders Dalsgaard Levring, Copenhagen, Denmark, assignors to Johan Robert Carp, Amsterdam, Netherlands, and Arthur Abraham Ruben, Berlin-Charlottenburg, Germany

Application July 28, 1933, Serial No. 682,692
In Denmark January 28, 1933

12 Claims. (Cl. 62—89.5)

The invention relates to a refrigerating apparatus for the storage or preservation of food, delicacies and the like.

The use of such apparatus is at the present time increasing progressively, both for household purposes and for use in shops and the like, and indeed to such an extent that such apparatus must be regarded already as indispensable for shops of a certain type. A disadvantage associated with the apparatus of known type in the last-named sphere of application is, however, that it is not at the same time suitable for showing or displaying the goods, because the apparatus is always in the form of closed cabinets (refrigerators), which is easy to understand in view of the fact that a good heat insulation is necessary.

In order to overcome this drawback, special refrigerators are already made for show windows and for other display purposes. The walls of these refrigerators are of glass and quite transparent. In order that the necessary heat insulation may be obtained in this construction it is necessary to use at least three glass plates, arranged one behind the other, for each wall. The glass plates can then, however, easily become coated with moisture owing to the difference in the temperature. Moreover, a threefold glass plate absorbs so much light and its composition changes to such an extent that the goods exposed to view appear to have a different colour from their real one. For example, it is certain that meat appears to be less fresh than it is. This unfavourable influence on the appearance of the goods is, naturally, extremely undesirable when the refrigerator is intended to be used as a display refrigerator cabinet.

Finally, all known forms of construction of refrigerating apparatus such as mentioned above are expensive, especially also owing to cabinet structure itself.

According to the present invention, all these disadvantages are overcome owing to the fact that the part of the refrigerating apparatus which gives off the cold is constructed as a surface located freely in space on which the goods to be cooled can be placed so as to be freely exposed to view, and the cooling capacity of the apparatus is so great that the temperature of the surface which may be made in any suitable

form can be kept so low that white frost is formed thereon.

It will be evident that the said surface may be used directly for instance as a table, display board, or the like. The appearance of such a surface is rendered particularly attractive by the white frost which is formed thereon. Its use is not associated with a single difficulty, and it differs advantageously from the somewhat complicated arrangement of the known refrigerators. 10 It is quite certain that the cooling effect can be sufficiently powerful. Also a cooling effect will be exercised over a wide area, which is very valuable, particularly in many shops, restaurants and the like.

In many cases this apparatus has the great advantage that articles which otherwise quickly become stale or lose their freshness, can now be kept in good condition for a much longer time than hitherto, which renders it possible for a 20 large selection to be kept in stock. Moreover, the dimensions of the available cooling space can be made very great in a simple manner, because one is not subject to all kinds of limitations as to space as in the case of cabinets.

Owing to the low temperature of the surface itself, which for the sake of the formation of white frost of course is always kept at at least 0° C., it is also possible to produce freezing in a 30 simple manner. Whipped-cream tarts when placed directly on the cooling surface, and in certain cases preferably on a metal dish, freeze on the lower side and thus retain a firm base, and thus the disintegration which is so unpleasant is prevented.

In a typical embodiment of the invention the surface which gives off the cold contains channels, pipe-coils or the like which form the evaporator of a compressor refrigerating plant or a guideway for a refrigerating medium (brine, for instance a solution of sodium chloride). When used as a table, display board or the like, the under side of the plate including the channel system is preferably covered by a layer of heat insulating material and enclosed with it in a 45 frame so as to produce a good insulating effect. The frame, made for instance of metal, should not be cooled down to a low temperature and must be so well insulated that no white frost or condensation water is formed thereon.

Various forms of construction of the invention are illustrated in the annexed drawing, in which:—

Fig. 1 is a diagrammatical representation of a cooling apparatus according to the invention which operates with a compressor.

Fig. 2 shows a plan of a cooling plate used therewith.

Fig. 3 shows a method of attaching a pipe-coil conducting the cooling agent to the surface plate.

Figs. 4, 5, 6 and 7 are cross sections of various forms of construction of the frame embracing the cooling plate and the appropriate method of attaching the plate therein.

In Fig. 1, 1 is the electro-motor, which drives a compressor 3 by means of a belt transmission 2. The motor 1 also directly drives a fan 4 which is arranged opposite an air cooler 5. If necessary, this air cooler may of course be replaced by a water cooler, in which case the fan 4 mostly may be omitted. The gas (SO_2, NH_3 or the like), condensed by the compressor, passes through the piping 6 into the cooler 5, from there passes through the piping 7 and then arrives in the expansion valve (throttling nozzle or the like) 8. In the cooler 5 the gas should be condensed to a liquid. The gas expands in the expansion valve 8 in known manner, thus producing cold which is given off to the plate 9. The expansion valve 8 may, of course, be constructed in various manners and may, for instance, also be self-regulating. In this case the adjustment can be controlled either by the gas pressure or by the temperature of the plate 9. After the working medium has given off its cold, it flows through the piping 10 to the suction side of the compressor. The piping 10 is of such length, if necessary arranged in one or more coils 11, that the working medium is always able, even when the temperature of the surroundings is low, to give off its excessive cold to the surrounding air, (when this cannot be done completely by the plate 7) before it again reaches the compressor 3. At the same time it is thus also possible to give the plate an inclined position, for instance, because the pipes can then yield sufficiently to permit it.

In Fig. 1 the plate 1 is surrounded by a frame 12 which is insulated from the plate and thus cannot assume a low temperature. The frame extends above the plane of the plate 9 to serve as a border or rim which sharply delimits the frosted area that forms upon the refrigerated plate.

Fig. 2 shows how the piping coming from the expansion valve may be arranged under the plate 9. The piping enters at 13 and then runs in bent formation along the lower side of the plate 9. The piping 10 leaves at 14. It is recommendable to combine the points 13 and 14 in such a manner that only one opening need be made in the table. It is much easier then to make the tubes fit airtight in the opening, which is very necessary as will be pointed out hereafter. It is, of course, important that the pipe coil under the plate 9 should be in good thermally conductive connection with the said plate 9. This can best be done by soldering or welding (for example spot welding) when the pipe coil is made as a separate unit. If necessary, however, the pipe coil may also be integral with the plate 9, so that, so to speak, a hollow plate is obtained and the refrigerating medium circulates directly in the plate itself. A method of attachment of a pipe coil made as a separate unit is shown in Fig.

3. Here, for instance the pipe 15 is soldered to the plate 9 by means of an ample proportion of an alloy of low melting point (for example Wood's or Roses metal). The advantage of such an alloy is that the soldering can, for instance, be carried out by immersing the plate in hot water. With this low temperature one may be sure that no buckling, warping or other deformation of the plate 9 can occur, which is very important as naturally the plate 9 must be kept 10 as flat as possible.

It is evident that it is also possible by means of the refrigerating plant to cool a solution of sodium chloride or the like to, for instance, 15°C . below zero, and then cause this solution to run along the bottom of the plate 9 or to circulate therein. There is therefore a certain accumulation of cold available, and it is then also possible to fit the plate 9 on already existing refrigerating plants. Moreover, the latter is possible in any case.

Fig. 4 shows how the plate 9 can be secured in the frame 12. On the upper side this plate 9 is surrounded, for instance, by a strip of rubber 16 (in some cases for instance also by a rubber tube filled with cork) against which the plate 9 is pressed by means of the screws 17. Immediately against the underside of the plate there are disposed small strips 18 of cork, supported by small strips 19 of wood, against which small plates 20 of fibre, bakelite or the like are pressed. The screw 17 co-operates with a nut 21, likewise made of insulating material such as fibre or the like. In this manner the plate 9 can be exactly adjusted, while a very great resistance is offered to the transmission of heat between the plate 9 and the frame 12. The resistance is further increased in that the plate 9 is allowed to come into contact with the rubber 16 and the cork 18 only along a very narrow edge.

The space below the plate 9 and therefore about the pipe coil 22 is filled with an insulating mass 23, e. g. cork, the joints of which are carefully filled up with capoc, slag wool or the like. Furthermore, the whole is enclosed by a plate 24 so as to form a water-tight unit. Thus no water deposited from the air can drop down on to the lower side. It is of importance of course, that no air can enter into the space between the plates 9 and 24, because if there would arise some air circulation, also white frost would be formed there and this would decrease the cooling action at the upper side considerably, while besides a lot of condensation water could be formed within the insulating mass. Owing to its large surface the frame 12 can easily assume the temperature of the surroundings, and therefore does not become covered with white frost, and does not even become coated with moisture. Preferably, the plate 9 is coated with nickel and then sanded, while the frame 12 may be coated with chromium, so that a very bright appearance is got together with the layer of white frost. The frame 12 is best made in the manner of extruded metal. The special profile will be clearly seen from the drawing.

Fig. 5 shows a further form of the construction. In this case the plate 9 is clamped between two strips of rubber 25 and 26, which are held in place by small blocks of wood 27, cork plates 28 being interposed if necessary.

Fig. 6 shows a further form of construction. Here also the plate is clamped between two strips of rubber 29, 30. In this arrangement the plate 9 can again be adjusted by means of screws 31. Further the rubber is as far as possible entirely enclosed at the upper side by an overturned edge 75

32 of the frame and at the lower part by a corresponding overturned edge 33 of the bearing plate of the screw 31. In this manner the rubber is removed from sight as far as possible, and exposed as little as possible to the action of moisture, while the heat transmission between the plate 9 and the frame 12 is not substantially increased by the contact of the overturned edges 32 and 33 with the plate 9, such contact being not more than a point-to-point one.

Fig. 7 shows a construction in which all the component parts are of bent metal. It is suitable for use, for instance, when rustless steel is used for the frames. The insulation is in the form of a rubber cord 34. In other respects the figure speaks for itself.

An easy manufacture of the plate is obtained if the surface plate 9 is given round corners. Then an endless strip of rubber provided with a groove is disposed under slight tension around the edge of the plate 9. The frame 12 may consist in this event of two parts, each of which is adapted to be thrust sideways over the plate, a groove in it surrounding the rubber strip. Thereafter the two parts may be attached together, and then they form a stiff frame, in which the plate 9 is supported.

It may be added that the refrigerating plates according to the invention may also be constructed, for instance, as covers of an ordinary refrigerator cabinet, in certain cases as a cover extended beyond this cabinet. Both the plates and the cabinet can then be operated in a simple manner by the same refrigerating mechanism. In certain cases a change-over device might be provided to connect the refrigerating machine with the refrigerator cabinet and the refrigerator plate as desired.

What we claim is:—

1. A device for the preservation and display of perishable goods comprising a display surface freely exposed in open air, means for refrigerating said surface, said means being of sufficient capacity to maintain a coating of white frost on said surface by moisture withdrawn from air circulating over said surface, a frame surrounding said surface and projecting above the same, and means insulating said frame from said surface whereby the frosted area of the surface is sharply delimited from the unfrosted surface of the frame.

2. A device for displaying and preserving perishable goods comprising a display surface freely exposed in open air, said surface constituting the upper member of a body containing passages constituting a conduit for refrigerating medium, a refrigerating apparatus adapted to supply refrigerating medium to said passages in sufficient quantity to maintain a coating of white frost on said surface, and a frame surrounding said surface and insulated therefrom whereby the frosted area of the surface is sharply delimited from the unfrosted surface of the frame.

3. A device for displaying and preserving perishable goods comprising a display surface freely exposed in open air, consisting of a plate of heat conductive material, pipe coils positioned beneath said surface and in heat conductive relation thereto, a refrigerating apparatus adapted to supply refrigerating medium to said coils in sufficient quantity to maintain a coating of white frost on said surface, a frame surrounding said surface and projecting above and below the same, heat insulating material between said plate and frame, and heat insulating material substantially

filling the space below said plate and within the downwardly projecting portion of the frame whereby the frosted area of the surface is sharply delimited from the unfrosted surface of the frame.

4. A device as defined in claim 3 wherein said display surface is a metal plate and the pipe coils are soldered to the under side of said plate with a substantial amount of a low melting alloy.

5. A device for displaying and preserving perishable goods comprising a display surface freely exposed in open air, means for refrigerating said surface, said means being of sufficient capacity to maintain a coating of white frost on said surface, and a frame surrounding said surface and sufficiently insulated therefrom that it will not be chilled low enough to cause the deposition of white frost thereon whereby the frosted area of the surface is sharply delimited from the unfrosted surface of the frame.

6. A device for displaying and preserving perishable goods comprising a freely exposed display surface, means for refrigerating said surface, said means being of sufficient capacity to maintain a coating of white frost on said surface, and a metallic frame surrounding said surface and sufficiently insulated therefrom that it will not be chilled low enough to cause the deposition of white frost thereon whereby the frosted area of the surface is sharply delimited.

7. A device for displaying and preserving perishable goods comprising a freely exposed display surface constituting the upper member of a body containing passages constituting a conduit for refrigerating medium, a layer of heat insulating material on the under side of said body, a refrigerating apparatus adapted to supply refrigerating medium to said passages in sufficient amount to maintain a coating of white frost on said surface, and a frame enclosing said body and insulating material, said frame being sufficiently insulated from said body that it will not be chilled low enough to cause the deposition of hoar frost thereon whereby the frosted area of the surface is sharply delimited.

8. In a device for the preservation and display of perishable goods, the combination with a substantially air-tight body comprising a frame, a plate forming the upper surface of the body, refrigerating conduits within the body and in heat-transfer relationship to said plate, a layer of heat insulating material within said frame beneath said plate and adjacent said conduits, and means insulating said frame from said plate to prevent cooling of said frame low enough for the deposition of hoar frost thereon, of refrigerating apparatus for supplying a refrigerating medium to said conduits in quantity sufficient to maintain a coating of white frost upon said plate by moisture withdrawn from air circulating over the same.

9. A device for displaying and preserving perishable goods comprising a freely exposed display surface, means for refrigerating said surface, said means being of sufficient capacity to maintain a coating of white frost on said surface, and a frame surrounding said surface and insulated therefrom by a strip of flexible insulating material having a relatively small area of contact with said surface whereby the frosted area of the surface is sharply delimited.

10. A device as defined in claim 9 wherein the insulating strip is compressed between the plate forming the display surface and the frame by means of screws bearing on said plate and sup-

ported in threaded members attached to said frame below said plate.

11. A device as defined in claim 9 wherein the insulating strip is compressed between the plate forming the display surface and the frame by means of screws bearing on said plate and supported in threaded members of insulating material attached to said frame below said plate.

12. A device as defined in claim 9 wherein the

insulating strip is compressed between the plate forming the display surface and the frame by means of screws bearing on the under side of said plate through further insulating material and supported in threaded members attached to said frame below said plate.
